UNITED STATES PATENT OFFICE

HELMER THORNGREN, OF DETROIT, MICHIGAN

SKATE SHARPENER

Application filed April 11, 1927. Serial No. 182,643.

The present invention pertains to a novel skate sharpener having for its principal object a device which may be used at a skating rink or on the ice to sharpen a 5 skate while on the foot of the skater.

The construction which enables the realization of this object consists essentially of a frame or housing supporting a vertically adjustable motor which carries an abrasive 10 wheel. This adjustability of the motor permits regulation of the effective cutting edge with reference to a fixed support for the skate. The invention includes further a suitable guide and travelling member which 15 restrict the skate to a definite straight line path over the cutting edge. The skate, after being properly adjusted with reference to the guide and travelling member, is oscillated over the cutting edge merely by a corresponding swinging movement of the leg 20 of the skater.

The invention is fully disclosed in the following description and in the accompanying drawings, in which—

25 Figure 1 is a plan view of the device;
Fig. 2 is a side elevation thereof, partly in section;
Fig. 3 is a front end elevation;
Fig. 4 is a detail horizontal section showing the supporting means for the motor;
30 Fig. 5 is an elevation of the skate clamp;
Fig. 6 is an elevation of the clamp at right angles to Figure 5; and
Fig. 7 is a detail vertical section.

35 Reference to these views will now be made by use of like characters which are employed to designate corresponding parts throughout.

The frame or casing of the device comprises a housing 1 of box-like construction standing on legs 2.

The frame is further provided with an upper yoke 3 having its sides 4 riveted to the sides of the member 1 and extended in the form of additional legs 5. To the members 3—4 are pivoted another pair of legs 6 which swing outwardly with respect to the frame in order to provide a lateral support in the manner illustrated in Figure 3.

50 One of the walls of the housing 1 is struck

inwardly to form a support 7 lying in a vertical plane and inclined to the axis of the housing. The inner face of the wall carries a bent strap 8, and the outer face carries a pair of spaced vertical bars 9, and 55 the members 8 and 9 are fixed to each other and to the wall by pins 10 as shown in Figure 4. This structure provides a support for a motor 11 having its base 12 equipped with a pair of channel shoes 13 slidable on 60 the bars 9. A boss 14 extends from the base 12 through a slot 15 cut in the wall 7. A screw 16 threaded in the boss passes through a slot 17 in the back of the strap 8, and the motor assembly may be locked in any desired position vertically of the slot 17 by a nut 18 threaded on the screw 16 and adapted to be clamped against the outer face of the strap 8. The motor is raised and lowered by a vertical screw 16' having a head 17' 70 which rests on the top of the casing 1. Current is supplied to the motor by a conductor 19 leading from any external source of current and passing through a wall of the housing 1 as indicated by the numeral 20 in Figure 2. The supply of current may be controlled by a switch disposed at any convenient position.

75 The shaft 21 of the motor carries an abrasive wheel 22 having a portion thereof projected through a relatively short slot 23 cut in the top of the casing 1. It will be seen that the wheel 22 is disposed at an acute angle to the axis of the housing due to the support of the motor on the inclined wall 7 80 and the slot 23 is cut accordingly. Adjacent the slot however is a guide plate 24 lying parallel to the axis of the housing.

85 At one edge of the housing is secured a vertical guide plate 25 by means of angle irons 26. The skate 27 which is to be sharpened while on the foot of the skater is placed longitudinally of the housing, against the guide 24, and consequently spaced from the guide 25. In order to restrict the movement of the 90 skate to a straight path axially of the housing, there is provided a spacing member comprising the body or intermediate part 28 and legs 29 and 30 extending from the ends thereof at right angles thereto and to each other. 95 100

The leg 29 has a pivot lug 31 to which is pivotally attached a clamping arm 32. The end in line with the intermediate section 28 has a lug 33 adapted to engage this end. Two such devices are applied to the ends of the skate, and the blade is received between the members 28 and 33. The upper end of the arm 32 has an internally threaded boss 34 accommodating a screw 35 which bears against the arm 29. By means of this screw the boss 34 may be spaced from the arm 29 whereupon a clamping action is effected on the blade at the other end. The section 28 serves as a spacer between the guides 24 and 25, as shown in Figure 3, and the arm 30 is doubled over as at 36 to form a shoe or clip straddling the guide 25 and slideable along the same.

In the operation of the device the user applies the clamps 28-36 to the ends of the skate while on the foot as shown in Figure 2. The foot is moved along the guides while the motor is in operation. Obviously the skate will be confined to a straight line path by virtue of guide and spacer constructions already described. The skate is prevented from being carried off the longer guide 25 first by a rise 37 at each end of its upper edge and next by stop pins 38 passing through the upper corners thereof and engageable by the clips 30, 36 in the event that these members are carried as far as the pins.

The apparatus may be carried from place to place by the yoke 3, and the several pointed legs thereof permit it to be rested on an ice surface without slipping. The extent of projection of the wheel 22 through the slot 23 is governed by the adjustment of the screw 16 vertically of the slot 17 in the strap 8.

Although a specific embodiment of the invention has been illustrated and described, it will be understood that various alterations in the details of construction may be made without departing from the scope of the invention as indicated by the appended claim.

What I claim is:—

A skate sharpener comprising a frame, a motor adjustably mounted in said frame, an abrasive wheel mounted on the shaft of said motor, said abrasive wheel slightly extending through a slot in said frame, a guide plate spaced from said wheel and at a substantial acute angle to the axis of said wheel, said guide plate being formed with up-curved ends, a skate clamping member slideable on said guide plate and adapted to support the skate, the up-curved ends of the guide plate being adapted to rock the skate while in contact with said wheel, and a second guide member disposed adjacent said wheel for direct engagement with the skate.

In testimony whereof I affix my signature.
HELMER THORNGREN.
